UNITED STATES PATENT OFFICE

ARTHUR S. WHITEHEAD, OF SEATTLE, WASHINGTON

SPARK ARRESTER AND SILENCER

Application filed September 23, 1929. Serial No. 394,478.

The invention is a device that may be placed at the upper end of a stack or the like which will prevent sparks passing out of the stack and also eliminate the noise of an engine or other device to which the stack may be connected.

The object of the invention is to provide mechanical means for arresting the sparks passing out of stacks or the like.

10 Another object of the invention is to provide a spark arrester which will also eliminate noise.

Another object of the invention is to provide a spark arrester which is so constructed 15 that it will cause practically all oil passing out of a stack upon which it may be placed to burn.

A further object of the invention is to provide a spark arrester which is so constructed 20 that it will automatically operate to increase or decrease the area of the passage therethrough as the pressure of the exhaust gases increases and decreases.

And a still further object is to provide a 25 mechanical movable screen adapted to be placed upon a stack or the like to arrest sparks that are passing therethrough which is of a comparatively simple and economical construction.

30 With these ends in view the invention embodies a funnel shaped housing adapted to be installed upon the upper end of a stack, an inverted conical member in the funnel shaped member and spaced apart therefrom, a plurality of movable baffles rotatably mounted in the outer edge of the conical member and adapted to rest on the outer edge of the funnel shaped member, and a chamber enclosing the said device and having a comparatively small opening in the upper end.

Other features and advantages of the invention will appear from the following description taken in connection with the drawing, wherein:—

45 Figure 1 is a vertical section through the surrounding chamber showing one side of the spark arresting apparatus therein broken away on a center line.

Figure 2 is a detail showing the means for 50 mounting the baffles.

Figure 3 is a detail showing a plan view of the baffles in raised or open position.

Figure 4 is a cross section through a portion of the baffles showing the baffles in the closed position.

55 Figure 5 is a detail showing one of the smaller baffles.

Figure 6 is a similar view showing one of the larger baffles.

In the drawing the device is shown as it would be made wherein numeral 1 indicates the spark arresting apparatus, numeral 2 a stack upon which the spark arrester may be placed and numeral 3 the silencing chamber.

A spark arresting apparatus 1 is formed 65 with a funnel shaped member 4 which is provided with a circular flange 5 having a shoulder 6 at the intersection of the flange and lower end of the funnel. The flange 5 is placed around the upper end of the stack as shown 70 with the shoulder resting upon the top of the stack. In the center and above the member 4 is an inverted conical shaped member 7 which is held in the position shown by spacers 8. It will be noted that the gases passing upward 75 out of the stack will strike the cone and the liquids such as oil therein will be deposited upon the heated surface of the cone and will burn. At the upper end of the cone is a circular horizontal flange 9 having a continuous recess 10 in the outer edge in which the baffles 11 and 12 are freely held. A guard 13 is placed upon the top of the flange 9 and held by bolts 14 as shown in Figure 1, how-

ever, it will be understood that this member may be held in place by any other suitable means. Shims may be placed between the guard and the flange 9 as shown in Figure 2 so that some or all of them may be removed to take up wear of the hubs of the baffles. The guard is formed by a downwardly inclined flange 15 which extends outward as shown in Figure 2. The member 13 is also provided with a continuous recess as indicated by the numeral 16 and it will be observed that the recess 16 corresponds with the recess 10, and hubs which are formed at the inner ends of the baffles 11 and 12 are freely mounted in the space formed between these recesses.

80 85 90 95 100

The baffles 11 and 12 are formed as shown in Figures 3 to 6 inclusive and it will be noted that their upper surfaces are V shaped so that the lower surface of the upper baffle 5 will rest upon a point or points and will not contact with a flat surface. The lower baffles 12 are made as shown in Figure 6 with a flat lower surface and the upper surface downwardly inclined from a central point 17 thereby forming comparatively thin edges 18 at the sides. The edges are inclined inward from the points 19 and the upper portion is comparatively narrow as shown. At the upper end of the upper portion 10 is a hub 20 which, as hereinbefore stated, is freely mounted in the space formed between the recesses 10 and 16, and at the lower end of the baffle is a ridge 21 the size of which may be changed to adjust the weight at the outer end of the baffles which will make it possible to regulate the movement of the baffles as the pressure varies and also makes it possible to relieve the back pressure of the engine. The upper and smaller baffle 11 is also 15 formed with a flat lower surface and inclined upper surfaces sloping upward from comparatively thin edges to a ridge at the center and this baffle is also provided with a hub at the upper end which is indicated by the numeral 22. These baffles may be made of any 20 suitable material, or of any other suitable design and arranged in any other suitable manner.

The chamber 3 is formed with a base which 25 may be attached to the stack in any suitable manner and a cylindrical casing 24 is placed upon the base and extends upward surrounding the spark arresting apparatus 1 as shown. At the upper end of the casing 24 is a horizontal plate 25 which is of substantial thickness as compared to the size of the chamber and this plate is provided with a comparatively small opening 26 at the center.

This plate being comparatively thick reduces the vibration to a minimum and thereby eliminates practically all the noise. Below the opening 26 is a cylindrical member 27 with openings 28 therein and below the member 27 is a conical shaped member 29 40 as shown. It will be noted that as the hot gases pass upward out of the stack 2 they will strike the cone 7 which will spread them outward and as they pass into the central part of the chamber 3 they will expand 45 and then as they pass upward through the comparatively small opening 26 they will contract and this expansion and contraction will assist materially in eliminating the noise.

It will be understood that changes may be made in the construction without departing from the spirit of the invention. One of which changes may be in the general design or arrangement of the spark arresting 50 apparatus or the use of baffles of a different

type or design, another may be in the use of other means for supporting the baffles, and still another may be the use of a silencing chamber of another type or design.

The construction will be readily understood from the foregoing description. In use the device may be placed upon the stack as shown and described and it will be noted that with the baffles in the downward or closed position there will be small openings 70 between the edges of the lower baffles and as the force of the exhaust gases or any gases passing upward through the stack increases it will raise the baffles and as it decreases the baffles will lower. In operation these baffles will move slowly upward and downward and apparently pulsate with a breathing motion. It will be observed that sparks passing upward through the stack will come into contact with the baffles and be extinguished or broken 75 up, and it will also be noted that by splitting up the gas stream as the gas finds its way to the atmosphere thru the small openings or slits between the baffles or blades a silencing effect will be produced. The noise vibrations 80 will be interfered with and eliminated due to the breaking up of the gas stream as it passes thru this pulsating screen.

Having thus fully described the invention what I claim as new and desire to secure by 95 Letters Patent, is:—

1. In a spark arresting and silencing device of the character described, a stack, a funnel shaped member at the top of the stack, an inverted cone above and spaced apart from the said funnel shaped member, a plurality of baffles pivotally mounted in the periphery of the said conical shaped member and overlapping the edge of the said funnel, means for limiting the upward movement of the said baffles, a cylindrical chamber surrounding the said baffles, said cylindrical chamber having a comparatively small opening at the upper end and a conical shaped baffle in the upper end of the chamber 100 and cooperating with said opening.

2. In a spark arresting apparatus, a conical shaped casing, an outwardly extending passage having a continuous opening extending around the periphery of the said casing, and a plurality of moving baffle plates pivotally mounted to extend across the outer end of the said opening.

3. In a spark arresting apparatus, a stack, a funnel shaped casing at the upper end of the stack, a conical shaped casing spaced apart and above the said funnel shaped casing, a plurality of movable baffles pivotally mounted in the outer edge of the said conical casing and extending across the opening between the two casings and means for limiting the upward movement of the said baffle.

4. In a spark arresting apparatus, a stack, a funnel shaped casing at the upper end of

- the stack, a conical shaped casing spaced apart and above the said funnel shaped casing, a plurality of movable baffles pivotally mounted in the outer edge of the said 5 conical casing and extending across the opening between the two casings, means for limiting the upward movement of the said baffles, and a chamber surrounding the said apparatus with a comparatively small opening at the upper end. 10
5. In a spark arresting apparatus, an outwardly inclined flange, a superimposed inverted conical shaped member above the said flange, said flange and member having a continuous opening between them and at the periphery thereof, a plurality of baffle plates pivotally mounted in the said superimposed member and extending across the said opening and resting upon the said flange, means 15 for limiting the upward movement of the said baffles, and means for taking up the wear of the said baffles at the point at which they are mounted. 20
6. In a spark arresting apparatus, an outwardly inclined flange, a superimposed inverted conical shaped member above the said flange, said flange and member having a continuous substantially horizontal opening between them and at the periphery thereof, a plurality of baffle plates pivotally mounted in the said superimposed member and extending across the said opening and resting upon the said flange and a plurality of superimposed pivotally mounted baffle plates above 30 and resting upon said former baffle plates and positioned to partially cover the cracks between them. 35
7. In a spark arresting apparatus, a casing, with a gradually enlarging opening at the upper end, a superimposed casing above the said former casing with an inverted conical shaped portion extending downward into said former casing, said casings having a continuous opening between them at the periphery thereof, a plurality of baffle plates, means for pivotally mounting the said baffle plates in the said superimposed casing in substantially a horizontal position with the said baffle plates held against the outer edge of said 45 former casing by gravity, and means for limiting the upward movement of the said baffle plates, said plates positioned to extend across the opening between the said casings and rest upon the former casing, and said plates forming a pulsating screen automatically operated by the varying pressures of gases passing between the said casings. 55
8. In a device of the character described, an inner member, an outer member positioned 60 to provide a continuous substantially horizontal opening between the said members, and a plurality of overlapping baffle plates pivotally mounted in the inner member and resting upon the outer member, said baffle plates held downward upon the outer edge of said 65 outer member by gravity forming a pulsating screen which automatically opens and closes as the pressures of a fluid passing between the members changes. 70
9. A pulsating screen comprising an inner casing, an outer casing, and a plurality of baffle plates pivotally mounted in one casing and adapted to be held upon the other by gravity to form a closure for a substantially horizontal opening between the said casings, 75 a plurality of smaller baffles also pivotally mounted in the same casing as the former baffle plates, superimposed above said former baffle plates and positioned to partially cover the cracks between said former baffle plates, 80 the width of said former baffle plates being comparatively small and the openings between them comparatively narrow to prevent sparks or the like passing therethrough. 85
10. In combination, a vertical pipe, an inverted conical shaped member located slightly above the upper termination of the said pipe, the upper end of said pipe having an outwardly inclined continuous flange, and a plurality of baffles forming a pulsating screen 90 hinged to the said inverted conical shaped member and resting upon the outer edge of the said flange. 95
11. In combination with a vertical exhaust pipe, a complete obstruction positioned slightly above the upper termination of the pipe and of a somewhat larger size than the pipe, and a continuous screen formed of a plurality of comparatively small members extending from the outer edge of said obstructing member and resting upon an outwardly flared extension of said pipe, said screen positioned in an inclined position with the members held downward by gravity and raised with a breathing motion by the rise in 100 the varying pressures of the gases of the stack. 105
12. In a spark arrester and silencer, in combination, a stack with an upwardly inclined outwardly flared flange, a superimposed casing above said stack and spaced above said stack flange closing the central portion of the stack and providing a continuous peripheral opening between the outer edge of said flange and casing, and a closure for said opening 110 adapted to be held and to move downward by gravity and adapted to be raised by varying pressures of gases in the stack, said closure providing a plurality of narrow escape 115 passages for the gases as it is raised thereby 120 preventing sparks in the gases passing therethrough and also splitting up the gas stream and destroying noise vibrations in said gases. 125
13. In a spark arrester and silencer, in combination, a stack with an outwardly extending flange, a casing superimposed above said stack providing a continuous peripheral opening at the outer edge of said flange with the central part above the stack closed, and a closure for said opening adapted to be 130

opened by increasing pressures of gases in
said stack and eliminating noise from said
gases by dividing same into thin streams as
it passes thru narrow openings formed in
said closure as it opens.

In testimony whereof he affixes his signature:

ARTHUR S. WHITEHEAD.
